EM 009017205-0001 * 5/2022
EM 015000604-0001 * 10/2022*Primary Examiner* — George D. Kirschbaum*Assistant Examiner* — Antoinette Martine Suiter(74) *Attorney, Agent, or Firm* — McGarry Bair PC(57) **CLAIM**

The ornamental design for a surveying instrument accessory as shown and described.

DESCRIPTION

FIG. 1 is a top perspective view of a surveying instrument accessory, showing my new design;

FIG. 2 is a bottom perspective view thereof;

FIG. 3 is a top view thereof;

FIG. 4 is a bottom view thereof;

FIG. 5 is a front view thereof; and,

FIG. 6 is a side view thereof.

Portions of the surveying instrument accessory shown in broken lines form no part of the claimed design.
